The ornamental design for a table-side information and point-of-sale (POS) device, as shown and described.

DESCRIPTION

FIG. 1 is a front and left perspective view of a table-side information and point-of-sale (POS) device showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear and right side perspective view thereof.

The broken lines in the drawings are shown for the purpose of illustrating portions of the table-side information and point-of-sale (POS) device and form no part of the claimed design. The article in which the design is embodied is a table-side information and point-of-sale (POS) device for use in a restaurant or hospitality environment.

The characteristic feature of the design resides in the overall appearance of the device.
